UNITED STATES PATENT OFFICE.

WINTHROP M. JAMESON, OF CAMBRIDGE, MASSACHUSETTS.

DEVICE FOR FORMING WIRE HAT-FRAMES.

No. 797,285.

Specification of Letters Patent.

Patented Aug. 15, 1905.

Application filed January 4, 1905. Serial No. 239,576

To all whom it may concern:

Be it known that I, WINTHROP M. JAMESON, a citizen of the United States, and a resident of Cambridge, county of Middlesex, State of Massachusetts, have invented an Improvement in Devices for Forming Wire Hat-Frames, of which the following description, in connection with the accompanying drawings, is a specification, like characters on the drawings representing like parts.

This invention relates to devices for forming twisted-wire hat-frames for ladies' hats; and it has for its object the production of certain novel features of construction and arrangement whereby the construction of the hat-frame is facilitated.

The various novel features of the invention will be fully described in the subjoined specification and particularly pointed out in the following claims.

Figure 1 is a partial sectional view of a device for forming wire hat-frames embodying my present invention, taken on the irregular line 1 1, Fig. 2, and to avoid confusion I have shown only two of the diametrically opposite supports provided with the supporting members for the round-and-round wires of the hat-frame. Fig. 2 is a top or plan view of the device shown in Fig. 1, only two of the supports being shown as provided with the wire-supporting members.

The base is shown in Fig. 2 as comprising two semicircular parts or members 1 and 2, hinged together at 3, the part 2 being firmly attached by screws 4 to a disk-like head 5, Fig. 1, secured to or forming part of a depending tubular shank 6, adapted to slip down over an upright post 7, rigidly secured to a table or other suitable stand 8. (Shown in section in Fig. 1.) A slotted ear 9 on the part 1 of the base adjacent its periphery has pivotally mounted thereon at 10 a combined locking member and collapsing member 11, said device being notched at its inner end at 12 to normally embrace the part 1 and the disk 5. By lifting the member 11 the toe 13 thereof is withdrawn from the disk and the part 1 of the base can be swung upward on the hinge 3 as a fulcrum to thereby collapse the base, this operation being effected when it is desired to removed a completed hat-frame.

The locking device forms no part of my present invention and is not claimed herein.

A series of L-shaped supports are carried by the base, and in the present embodiment of my invention said supports are shown as

integral with the base portions 1 and 2, each support comprising a radial foot 14 and an upright portion 15, (see Fig. 1,) the feet or extensions 14 projecting radially beyond the base. Each support is slotted, as at 14^x 15^x, (see Fig. 1,) and on one vertical face each support is recessed to leave shoulders 16 and 17 at right angles to each other. A head-wire-supporting member, shown as a short flat metal arm 18, is adjustably connected with the upright portion 15 of each L-shaped support by a headed clamping-bolt 19 and nut 20, (see Fig. 2,) the head of the bolt being cut away at 21 to rest against the shoulder 17, thereby preventing rotation of the bolt when the nut 20 is set up or loosened. By easing up on the nut the member 18 can be raised or lowered with relation to the base and also adjusted radially about the clamping-bolt as a center to provide for the size variations in the head-wires, the head-wire being indicated in Fig. 1 by dotted lines at h. Each of the head-wire-supporting members has formed in its outer edge a wire-seat 22, opening outward or at the outer edge of the member.

Crown-wire-supporting members are shown as elongated and longitudinally-curved flat arms 23, preferably made of flat metal, and each having a wire-seat 24 at or near its upper end, the lower end of said member 23 having an elongated curved slot 25 to receive the shank of a headed clamping-bolt 26, passed through the slot 15^x of the upright portion of each of the L-shaped supports and having its head shaped substantially as has been described with relation to the heads of the clamping-bolts 19, nuts 27 setting up the bolts and holding the members 23 in adjusted position. These members are of such length and shape, as will be seen by reference to Fig. 1, that their wire-seats 24 are located above the head-wire-supporting members, and by adjusting the members 23 the general shape and dimensions of the crown-wire c (see dotted lines, Fig. 1) can be varied within relatively wide limits.

As a matter of practice the main adjustment of the head-wire-supporting members will be radial only to increase or decrease the diameter of the head-wire, the variations in the height of the crown and its lateral dimensions being secured by adjusting the supporting members 23. The radial portions or feet 14 sustain the brim-wire-supporting members, and some of the latter may also be sustained on the upright portions of the L-shaped sup-

ports. I have shown herein both arrangements to illustrate clearly the elasticity or scope of the device.

The right-hand foot 14, Figs. 1 and 2, is shown as sustaining two rather short and only slightly curved brim-wire-supporting members 28, each having a wire-seat 29 and a longitudinal slot 30, the two members 28, which are sustained by the foot, being adjustably connected therewith by a clamp device, such as has been described hereinbefore, the head of the clamping-bolt being cut away at 21 (see dotted lines, Fig. 1) to coöperate with the shoulder 16. These members 28 can be moved in and out along the member 14, and they can also be adjusted vertically and angularly with relation thereto and with relation to each other, a single clamping device serving to hold the pair in adjusted position. On the foot 14 (shown at the left in the drawings) I have illustrated two brim-wire-supporting members 28^x, each having a wire-seat and a longitudinal slot, as has been described of the members 28, but the members 28^x are longer and have slightly more curvature, so that a peculiarly-shaped brim may be provided for. These two members 28^x are shown as adjustably connected with the upright shoulder 15 of the L-shaped support by a single clamping device of the character hereinbefore referred to, and said clamping device is also utilized to hold in place the adjacent crown-wire-supporting member 23. As to the grouping or particular adjustment of the crown and brim wire supporting members, that is open to the convenience of the operator, so that whichever arrangement most readily adapts itself to the shape of the hat-frame to be made can be adopted.

As the device is shown, set for the formation of a hat-frame having a peculiarly-shaped and flared brim at its front, I have mounted on the left-hand foot 14 a long supporting member 31, having several wire-seats 32 and an elongated slot 33, through which is passed the shank of one of the clamping-bolts 26, the member 31 being adjustable on the foot 14 independently of any of the other supporting members carried by that particular support.

I find it is convenient at times to assist the operator in throwing on or placing the round-and-round wires by means of substantially radial guide-wires attached to the brim-wire-supporting members of a group and to the corresponding head-wire-supporting member, and such a guide-wire is shown at *g*, Fig. 1, its outer end being attached in any suitable manner to the member 31, as by a thumb-nut 34, the wire being led through holes 35 in the two members 28^x and 18 and fixedly secured to the latter, each wire being located just beneath and as close as possible to each of the wire-seats 29^x and 22, respectively. When the operator applies the round-and-round wire, it is thrown onto this guide-wire, and the latter

serves to direct it quickly and easily up to the wire-seat of the particular supporting member which is to sustain it. Each group of wire-supporting members on any one of the L-shaped supports may be provided with a guide-wire, or they may be used on only such groups as will facilitate the work. When the frame is completed by the usual attachment of the fore and aft wires to the round-and-round wires in a manner well known to those skilled in the art, the frame can readily be removed by releasing the locking device 11 and collapsing the base, whereby the wire-supporting members on the part 1 of the base will be moved a slight distance toward the members on the fixed part 2 of the base, so that the frame can be lifted off without distortion or other derangement of its shape. By making the crown-wire-supporting members 23 curved in the direction of their length they extend well inside of the head-wire-supporting members 18 and provide a clear and open space for the operator to work in when laying the wires of the frame.

By reference to Fig. 2 it will be seen that the crown-wire-supporting member 23 at the right is set out from the nearer side of the upright 15, this being necessary to clear the clamping-nut 20, which holds in position the head-wire-supporting member 18, and such offsetting of the member 23 is effected by interposing a thick washer 40 between the member and the nearer face of the upright 15. The same device is employed to offset the members 28^x and 23 at the left, so that the clamping-nut 20 for the head-wire-supporting member on that side will be cleared, thus avoiding any interference of parts when the supporting members are adjusted.

Having fully described my invention, what I claim as new, and desire to secure by Letters Patent, is—

1. In a device for forming wire hat-frames, a base, a series of radial extensions thereon each provided with a rigid upright, separate head and crown wire supporting members adjustably and independently connected with each upright, said supporting members each having a wire-seat at its upper end, adjustable brim-wire-supporting members having wire-seats, and means to connect said members in adjusted position with the radial extensions.

2. In a device for forming wire hat-frames, a base, a series of rigid L-shaped supports thereon, the feet of said supports extending radially upon the base, separate head and crown wire supporting members adjustably and independently connected with the upright portion of each support, each member having a wire-seat at its upper end, brim-wire-supporting members, and means to adjustably connect them with the L-shaped supports.

3. In a device for forming wire hat-frames, a base, a series of rigid L-shaped supports thereon, the feet of said supports extending

radially from the base, short head-wire-supporting members adjustably connected with the upright portions of said supports, elongated, curved crown-wire-supporting members adjustably connected with said upright portions and adjustable independently of the head-wire-supporting members, and a plurality of brim-wire-supporting members, and means to adjustably connect them with the L-shaped supports.

4. In a device for forming wire hat-frames, a base, a series of rigid, longitudinally-slotted supports thereon arranged in radial planes, a plurality of longitudinally curved and slotted wire-supporting members carried on each support, and clamping devices extended through the slots in the supports and the supporting members to maintain the latter in adjusted position.

5. In a device for forming wire hat-frames, a base, a series of rigid, slotted L-shaped supports thereon, the feet of said supports extending radially from the base, a short head-wire-supporting member adjustably connected with the upper end of the upright portion of each support, a longitudinally curved and slotted crown-wire-supporting member on each of the upright portions and extended inside of and above the adjacent head-wire-supporting member, a clamping device to hold each crown-wire-supporting member in adjusted position, and a plurality of brim-wire-supporting members adjustably connected with each of said L-shaped supports.

6. In a device for forming wire hat-frames, a base, a series of rigid, slotted L-shaped sup-

ports thereon, the feet of said supports extending radially from the base, a short head-wire-supporting member adjustably connected with the upper end of the upright portion of each support, longitudinally-curved crown-wire-supporting members vertically and longitudinally adjustable on said upright portions, means to clamp said members in adjusted position, and brim-wire-supporting members adjustably connected with the radial, slotted feet of the supports, each wire-supporting member having a wire-seat formed in its outer edge.

7. In a device for forming wire hat-frames, a base, a series of rigid L-shaped supports thereon, the feet of said supports extending radially upon the base, separate head and crown wire supporting members adjustably and independently connected with the upright portion of each support, each member having a wire-seat at its upper end, a plurality of brim-wire-supporting members mounted on each of said supports and each having a wire-seat, and a guide-wire connected with each head-wire and brim-wire supporting member of a group below and adjacent the wire-seat, to readily guide the round-and-round wires to the seats when applied to the apparatus.

In testimony whereof I have signed my name to this specification in the presence of two subscribing witnesses.
